UNITED STATES PATENT OFFICE.

HENRY MARCUS QUACKENBUSH, OF HERKIMER, NEW YORK.

TARGET.

SPECIFICATION forming part of Letters Patent No. 426,063, dated April 22, 1890.

Application filed June 6, 1889. Serial No. 313,815. (No model.)

To all whom it may concern:

Be it known that I, HENRY MARCUS QUACKENBUSH, a citizen of the United States, residing at Herkimer, in the county of Herkimer and State of New York, have invented 5 certain new and useful Improvements in Targets, of which the following is a specification.

My invention relates to targets; and it consists in various features hereinafter set forth 10 and claimed.

In the drawings, Figure 1 is a face view of my improved target; Fig. 2, an edge view of the same; Fig. 3, a perspective view of the operating mechanism removed from the target, and Figs. 4 to 8 views illustrating certain 15 details.

In the practical use of targets difficulty has been experienced in so arranging the mechanism as to prevent the accidental ringing of 20 the alarm and the accidental release of the alarm and the accidental release of the 25 visual signal, the striking of the bullet against the face of the target often serving to release or operate them. Another serious objection to the targets now in use is the spattering of the bullets, which is liable to dangerously injure persons standing in proximity to the target. To overcome these objections, therefore, 30 is the object of the present invention.

A indicates a plate or frame by which the 35 target is to be secured in place, the said attaching-plate being secured at its lower edge to the rear face of the dial or plate G by means of posts a a. This attaching-plate sets away some distance from the rear face of the target proper, as shown, so as to permit the operating mechanism, which is carried wholly 40 by the plate, to be placed out of sight between the target and attaching-plate; and it is obvious that in lieu of the posts a a the lower end of the plate may be bent and attached directly to the target-dial.

Secured to or projecting from the face of the plate A are guides or slotted lugs b b, in which is mounted a rod or stem c, preferably, 45 though not necessarily, angular in cross-section, carrying at its upper end the signal or indicator, which is shown in the general form of a bird.

B indicates a coiled spring, one arm of 50 which is secured to the post or guide b or to the plate A, while the other arm is connected with the rod or stem c, the result of this ar-

angement being that the spring tends constantly to throw the rod or stem upward, so as to permit its visual signal to be seen above 55 the top of the target. The rod or stem c is held against upward movement by means of a locking device or mechanism, which when the bull's-eye is struck releases the rod and permits the spring to carry it up. This locking or dogging mechanism comprises a flat 60 U-shaped spring-arm C, secured at one end to the attaching-plate A, the opposite end of the arm carrying the bull's-eye D in line with the opening in the center of the dial of the 65 target, and being adapted to engage in a notch d in the rear face of the rod or stem c. At its free end the arm C is slotted lengthwise for a short distance, so as to form an arm e, which projects slightly from the front 70 face of the spring-arm and is designed to engage or enter the notch d in the rod or stem c. Now when the bull's-eye is struck the arm e is forced back out of the notch and the spring allowed to raise the rod.

At the free end of the arm C is a set-screw f, which bears against the rear face of the stem or rod c, the purpose of the screw being to regulate or control the extent to which the arm e may enter the notch d and make 80 the target more or less sensitive. When air-guns are used, the screw will be so adjusted as to permit the arm e to barely engage the rod c, for the reason that the blow that the slug or cartridge gives the bull's-eye 85 is very slight and just sufficient to disengage the arm, while in guns in which powder is used the blow given the bull's-eye is heavier, and consequently the screw will be so adjusted that the arm may enter fully into the 90 notch. Access is had to the screw through an opening in the plate A.

Between the rear face of the bull's-eye and the front face of the spring-arm C is placed a pad or cushion g, of rubber, leather, or equivalent material, to assist in taking up jars, the cushioning being principally effected, however, by the arm C, which serves not only the purpose just mentioned, but serves as a catch for the rod c and returns the bull's-eye to 100 place after it has been struck and moved backward.

E indicates a spring, one arm of which passes through the lower end of the rod or

stem *c*, while the other arm carries or supports a bell *F*, which latter is provided with a spring *h*, carrying a hammer *i*, as shown.

The arm *j*, that passes through the lower end of the rod or stem *c*, projects beyond the side face thereof, so that when the rod is released and rises the arm will strike against a pin or stud *k*, projecting from the front face of plate *A*, and by the sudden stopping set the spring *E* to vibrating. This will also cause the spring *h* to vibrate rapidly, thereby ringing the bell. Pin or stop *k* serves to limit the upward movement of the rod or stem *c*.

15 The dial *G* is provided with a rim or band *l*, which extends or projects forwardly from its periphery, while the bull's-eye is provided with a similar rim or flange *m*, the purpose of these flanges being to prevent the glancing 20 and spattering of the bullets. To further guard against this spattering of the lead, the face of the bull's-eye is provided with a series of concentric rings, or may be "checked," like the face of a file, or roughened in any 25 equivalent manner. If the face of the dial is roughened by means of the concentric rings, they would have to be made finer than the indicating-rings commonly used. Ordinarily the indicating-rings are cut into the face of the 30 dial; but in the present instance I press them in in such a way as to throw the metal up on each side of the groove, as shown, thereby preventing the spattering before alluded to and producing more distinct lines not easily 35 obliterated by use or by the paint applied thereto. Again, if the groove is cut into the plate and the metal removed, it is necessary to cut deeper to get the same depth of groove as is secured by pressing; but at the same 40 time the plate or dial is materially weakened and the ridges are not as sharp.

From the foregoing description it will be observed that I effectually guard against the spattering of the lead, that the target is strong, 45 simple, and cheap, and that there is little or no liability of the accidental actuation of the visual and audible signals.

In lieu of the spring *B*, a weight might be used; but I prefer the arrangement shown.

50 In setting the target it is only necessary to pull down upon the cord *o*, secured to the lower end of the rod or stem *c*, the tongue *e* springing into the notch as soon as the rod or stem is pulled downward sufficiently.

55 What I claim is—

1. In a target, the dial *G*, having its face roughened, substantially as and for the purpose set forth.

2. In a target, a dial having grooves or rings 60 pressed into its face.

3. In a target, a bull's-eye having its face roughened, substantially as and for the purpose set forth.

4. In a target, a dial *G*, having a rim or 65 flange *l*.

5. In a target, a bull's-eye *D*, having a rim or flange *m*.

6. In a target, the combination, with the flanged dial *G*, of the flanged bull's-eye *D*.

7. In a target, the combination, with a dial, 70 of an attaching-plate and operating mechanism mounted wholly upon the plate.

8. In a target, the combination, with a dial, of a plate, as *A*, secured to the rear face of the dial at its lower edge and set away a distance therefrom, and operating mechanism 75 independent of the dial carried by the plate.

9. In a target, the combination, with a dial and the plate *A*, of the visual signal, a spring-arm secured to the plate and adapted to engage 80 the visual signal, and a bull's-eye secured to the spring-arm.

10. In a target, the combination, with the dial *G* and plate *A*, of the rod or stem *c*, a spring-arm *C*, adapted to engage the rod, a 85 spring *B*, serving to operate the rod when released, and a bull's-eye *D*, carried by the spring-arm.

11. In a target, the combination, with the dial *G*, of the plate *A*, a rod or stem *c*, the 90 **U**-shaped arm *C*, interposed between the rod and plate and adapted to engage the former, a bull's-eye applied to the front face of the arm, a spring *B*, adapted to actuate the rod or stem, and a bell carried by the rod or stem. 95

12. In a target, the combination, with a dial, of a visual signal, an arm adapted to engage the signal rod or stem, a spring connected with the latter, and an adjusting device adapted to regulate the engagement of the spring-arm 100 with the rod or stem.

13. In a target, the combination, with a dial and a plate, of a rod or stem *c*, provided with a visual signal and a bell, and means for locking said rod in position. 105

14. In combination with plate *A*, rod *c*, provided with a notch *d*, spring-arm *C*, provided with an arm *e* to enter the notch, and a spring *B*, connected with the rod.

15. In combination with plate *A*, rod *c*, set 110 away from the front face thereof, arm *C*, secured at one end to the plate and adapted to engage the rod, a spring *B*, to operate the rod, and a set-screw *f*, passing through the free end of arm *C* and bearing against the rear face of 115 the rod or stem.

16. In a target, the combination, with the rod or stem *c* and means for moving said rod, of a spring *E*, provided with a bell and secured to the rod. 120

17. In a target, the combination, with a rod or stem *c*, of means for holding and releasing said rod or stem, a spring *E*, having one end passed through the rod and provided at its opposite end with a bell, and a pin or stud *k* 125 in the path of the arm of the spring.

18. In a target, the combination, with a rod or stem *c*, of means for holding and releasing the same, a spring *E*, secured to the rod, a bell secured to the spring, and a spring *h* and hammer *i*, carried by the bell. 130

19. In a target, the combination, with a dial, of a signal, a spring-arm, and a bull's-eye carried by the spring-arm.

20. In a target, the combination, with a dial, of a bull's-eye and a spring-arm supporting and adapted to return the bull's-eye to its place.
- 5 21. In a target, the combination, with a dial, of a spring-arm movable toward and from the rear face of the dial and a bull's-eye mounted upon the arm.
22. In a target, the combination, with a
- bull's-eye and its supporting-arm, of an interposed cushion.
- In witness whereof I hereunto set my hand in the presence of two witnesses.

HENRY MARCUS QUACKENBUSH.
